[57] CLAIM

The ornamental design for a front face of a black historical figures chess set, as shown and described.

DESCRIPTION

FIG. 1 is a top, left perspective view of a first side of the front face of a black historical figures chess set showing my new design;

FIG. 2 is a top, right perspective view of the first side thereof;

FIG. 3 is a top, right perspective view of a second side thereof;

FIG. 4 is a top, left perspective view of the second side thereof;

FIG. 5 is a front elevational view of a single chess piece thereof; and,

FIG. 6 is a left side elevational view of the chess piece of FIG. 5.

The broken line showing of the chess board in FIGS. 1-4 is for illustrative purposes only and forms no part of the claimed design.
